UNITED STATES PATENT OFFICE

ADOLPH LANGSNER, OF CHICAGO, ILLINOIS, ASSIGNOR TO EUGENE DIETZGEN COMPANY, OF CHICAGO, ILLINOIS, A CORPORATION OF DELAWARE

LEVELING ROD

Application filed August 29, 1927. Serial No. 216,305.

My invention relates to locking devices for extensible leveling rods for holding the upper section in positive, locked relation, in fully extended position relative to the lower section, so that this adjustment of the two sections cannot be inadvertently disturbed.

Heretofore, in the construction of these extensible leveling rods wherein the upper section carrying a target adjustable thereon is 10 slidable relative to the lower section, which is adapted to the position vertically on the ground or other support, it has been customary to provide an adjustable clamping device for firmly holding the upper section in its extreme extended position on the lower section. Experience has shown, however, that in the ordinary use of the leveling rod as thus extended, that after a measurement had been taken and the operator had 15 removed to a different position to take a new measurement, he invariably, in the act of re-positioning the lower section on the ground, permitted it to drop slightly and impact against the ground. The prior construction of clamping devices were not sufficiently effective to prevent the shock of impact of this lower section against the ground to prevent the upper section from moving downwardly slightly, thus disturbing 20 the exact and accurate setting of the upper section in its extreme extended position.

One of the objects of my present invention is to provide a locking device, and particularly an automatic locking device, for 25 positively and firmly holding the upper section from inadvertent movement relative to the lower section when the upper section is in its extreme extended position.

Another object of my present invention 30 is to so construct this locking device that it will come into operation automatically as the upper section is slid along, and upwardly, relative to the lower section, so that when the upper section finally reaches its extreme extended position it will be positively locked.

Still another object of my invention resides in providing such a locking device 35 of re-positioning the lower section on the 40 completely hidden from view when the sections

are in their non-extended or lowered positions.

Another object of my invention is to construct this automatic locking device with a yieldable member mounted on one of the 55 sections, preferably the lower, which member is adapted to give way to permit the other section to slide over it when shifted in one direction, but which member will instantly return to former position when the 60 other member has passed beyond it, so that the yieldable member will then be in a position to prevent the return movement of the 65 other member. By arranging this yieldable member to operate when the sections of the leveling rod are not in vertical position, the upper section will be held by the action of gravity, and the outward position of the yieldable member. This position will correspond to the extreme extended position of 70 the upper section.

These and other objects will be apparent from a perusal of the following specification when taken in connection with the accompanying drawings, wherein

Figure 1 is a sectional view of the upper and lower sections of my leveling rod when in lowered position.

Figure 2 is a corresponding view thereof when the upper section is in extreme ex- 80 tended position.

Figure 3 is a perspective view of Figure 2.

Figure 4 is a perspective view of one form of my spring interlock.

Figure 5 is a perspective view of the upper and lower sections of the leveling rod when in lower position.

Figure 6 is a similar view with the sections in fully extended position.

Referring now to the drawings, my extensible leveling rod comprises a lower section 2 and an upper or movable section 4; the lower section in use is adapted to be vertically positioned on the ground and the upper section slides vertically on the lower 85 section. These two sections are constructed so that a target may slide along either one. In taking certain measurements it is necessary to extend the upper section 4 so that the target on the upper section can be ad- 90 95

justed to greater elevations. In this instance the upper section is merely slid vertically upwardly to the lower section. Any desirable means may be utilized for holding the two sections in assembled relation, so that they may be free to slide upon each other relatively. In the present instance, I have shown the bottom portion of the upper section 4 provided with an ordinary type of U-shaped clip 6, which encloses the lower section 2. In addition, prior devices have been provided with clamping means, including cooperative parts on the slidable sections for firmly holding the sections in outwardly extended position. Heretofore such clamping means have taken several forms, but in the present illustration I have preferred to use the particular clamping means which I have shown, and which generally comprise a rectangular hollow sleeve 8 secured to the face of the upper portion of the lower section 2. This sleeve is adapted to receive and to have slide therethrough, the upper section 4, and this sleeve has been provided with an adjusting screw operated by a hand wheel 10 so as to press against and hold the sections firmly.

My present invention consists in means positioned on the relatively movable sections at definite points thereon and constructed and arranged so that when the two sections slide relatively, so that the outer section is in extreme extended position, the locking means will automatically come into action and will hold the upper section in such vertical position, so that such said adjustment cannot be inadvertently altered. The invention in this broad aspect may take several forms; as an exemplification of one form, I prefer that illustrated herein where the automatic locking means comprises a leaf spring 12 of resilient metal fastened by means of screws 14 to the face 16 of the lower section 2. The spring 12 is preferable of some length and extends longitudinally of the lower section 2 along such face 16. The spring 12 is slightly bent outwardly at a point 17 adjacent its lower end, so that when fastened in place on the section 2 the upper end of the spring will normally stand out from the face 16 of the lower section 2. The upper edge of the spring 12 is provided with laterally bent portions 18, which may take any shape but are preferably shown as spaced ears. These ears provide a substantially horizontal ledge or abutment against which the bottom end of the upper section 4 may contact or rest when in extreme extended position, as shown in Figures 2 and 3. If desired, this lower face of the upper section 4 may be faced with a metal strip 20 fastened in place in a seat thereon by means of screw 22. This facing prevents injury to the lower end 65 of the upper section 4 due to its contact

with the upper end of spring 12 or with the lower abutment 24, which is usually carried by the lower end of the lower section 2.

The spring 12 is arranged to lie flat against face 16 of the lower section 2 to permit the upper section to slide relatively thereto into its extreme extended position. To this end I preferably form the lower section 2 with a notch or pair of notches 26, directly opposite the ears 18 on the spring 12, so that when the spring is pushed inwardly the ears 18 will lie within the notches 26 and the spring can thus lie flat against the face 16. This permits the upper section 4 to slide over the spring and to move in either direction. When the upper section 4 is moved upwardly as shown in Figures 1 and 5, by reason of its resiliency it presses outwardly against the longitudinally extending ribs 27 on the inner face of the upper section 4 and holds these two sections from rattling movement. Due to the relatively broad face the spring 12 being wider than the distance between the ribs 27 on the inner or hidden face of the upper section 14, this spring 12 will press against the ribs only and will not press against the intermediate inner face of the section 4 which as is well known is provided with divisional markings. Thus these markings are not marred or scraped by the spring 12 when the two sections are adjusted. In this position the spring 12 is hidden from view. On the other hand when the upper section 4 has been slid along to its extreme extended position, as shown in Figures 2, 3 and 6, the lower end of the upper section 4 will clear the upper end of the spring 12, so that the spring instantly moves outwardly and the ears 18 which form the ledge, snap past the metal plate 20 on the lower end of the section 4 and thus, under the action of gravity of this upper section 4, hold it from downward movement; the upper section will thus be locked in its extreme extended position.

It will thus be seen that I have provided a very simple type of lock for accomplishing this purpose. The spring 12 as thus constructed is not only economical in manufacture and assembly, but it also is sure and positive in operation and permits the practically instant release of the upper section when once locked, as heretofore described, by merely pressing inwardly so that the ears house within the notches 24. It will also be apparent that when the two sections are in compactly arranged position, as shown in Figure 5, this spring, by pressing outwardly prevents them from rattling.

Having thus described my invention what I claim as new and desire to secure by Letters Patent is:

1. In an extensible leveling rod, the combination of a first section and an upper second section having divisional marks on

its obverse and reverse faces, the reverse face having outstanding ribs extending parallel thereto and a leaf spring secured to the lower section and operable between such reverse face and the adjacent face of the other section for holding the sections when slid relatively in extreme position of extended adjustment, said spring at its free extremity being wider than the width of the space between the ribs to engage the longitudinal ribs on the upper section whereby said spring is held out of contact with the divisional marks on said reverse face.

2. In a device of the class described, the combination of a lower section and an upper section slideable vertically thereon, said upper section having divisional marks on that face thereof which is adjacent to the face of the lower sections, said upper section having a longitudinal projection thereon and a leaf spring secured at one end to the lower section and adapted to contact against the longitudinal projection, said spring at its free extremity being adapted to bear against the projection to hold the upper section in extreme extended position relative to the lower section.

3. In an extension leveling rod, a lower leveling rod section, an upper section slideable on said lower section, one of said sections having a surface for receiving divisional marks, a longitudinal rib extending outwardly from said surface, and a leaf spring for locking said sections in extended position adapted to bear against the rib, said spring being carried by the other rod section, whereby the surface having the divisional marks will be free from engagement with said leaf spring.

40 In witness whereof, I have hereunto subscribed my name.

ADOLPH LANGSNER.
